DESIGN FOR A SCARF BLOUSE

Elisabeth Fischer, New York, N. Y.

Application July 17, 1937, Serial No. 70,504

Term of patent 7 years

To all whom it may concern:

Be it known that Elisabeth Fischer, a citizen of Germany and resident of New York, in the county and State of New York, has invented a new, original, and ornamental Design for a Scarf Blouse, of which the following is a specification, reference being had to the accompanying drawing, forming part thereof, in which the figure is a plan view of a scarf blouse, showing my new design.

The design is characterized by the contour of the scarf blouse as shown.

I claim:

The ornamental design for a scarf blouse, as shown and described.

ELISABETH FISCHER.
